Williamson & Merleau

UNITED STATES PATENT OFFICE.

HENRY C. ERBE, OF JAVA, SOUTH DAKOTA.

STARTER FOR INTERNAL-COMBUSTION ENGINES.

1,331,631.

Specification of Letters Patent.

Patented Feb. 24, 1920.

Application filed May 1, 1919. Serial No. 294,116.

To all whom it may concern:

Be it known that I, HENRY C. ERBE, a citizen of the United States, residing at Java, in the county of Walworth and State 5 of South Dakota, have invented certain new and useful Improvements in Starters for Internal-Combustion Engines; and I do hereby declare the following to be a full, clear, and exact description of the invention 10, such as will enable others skilled in the art to which it appertains to make and use the same.

My present invention has for its object to provide a highly efficient mechanical starter 15 for internal combustion engines; and, to this end, it consists of the novel devices and combinations of devices hereinafter described and defined in the claims.

In the accompanying drawings, which 20 illustrate the invention, like characters indicate like parts throughout the several views.

Referring to the drawings:—

Figure 1 is a fragmentary view, partly in plan and partly in section, of an automobile, 25 with some parts illustrated by means of broken lines, having the invention incorporated therein:

Fig. 2 is a detail view with some parts sectioned on the line 2—2 of Fig. 1, on an enlarged scale;

Fig. 3 is a front elevation of the part shown in Fig. 1; and

Fig. 4 is a view partly in front elevation and partly in vertical section taken on the 35 line 4—4 of Fig. 1, on an enlarged scale.

The invention is shown applied to an automobile of the "Ford" type and of the parts thereof, it is important to note the frame 5, floor 6, toe-board 7, dash 8, internal combustion engine 9, indicated as an entirety with the exception of its crank shaft 10 to which is secured a fan drive pulley 11 and starter ratchet pin 12, starter ratchet 13, starter clutch releasing spring 14, clip plate 15, and 40 radiator 16.

To mechanically start the engine 9, I provide a spring motor 17 carried by a shaft 18 intermediately journaled in a bearing 19 on the clip plate 15, in axial alinement with the 45 crank shaft 10. This motor 17, as shown, comprises a spring 20, encircling the shaft 18, a large disk 21 keyed to said shaft and having at its periphery a laterally and inwardly projecting annular flange within 50 which said spring is mounted, and a large spur gear 22 loosely journaled on said shaft

inward of the spring 20. Obviously, the disk 21 and its flange, together with the gear 22, afford a housing for the spring 20.

The inner end of the spring 20 is anchored 60 by a pin 23 to the gear 22 and its outer end is also anchored by a pin 24 to the disk 21. The gear 22 is held against axial movement on the starter shaft 18 by the hub of the disk 21 and a set screw-equipped collar 25 65 on said shaft. On the inner end of the starter shaft 18, is secured the starter ratchet 13 and the outer end of said shaft is made angular in cross section, at 26, to receive and hold a hand crank 27, as will presently appear. The spring 14 is compressed between the bearing 19 and collar 25 and yieldingly holds the starter ratchet 13 out of engagement with the starter pin 12.

To wind the spring 20 which, as shown, 75 is in the form of a clock spring, but, of course, may take any desired form, there is provided a spur pinion 28 which meshes with the gear 22. This pinion 28 is provided with a wide face to permit the required sliding movement of the gear 22 thereon, during the movement of the starter ratchet 13 into and out of interlocking engagement with the 80 starter pin 12. The pinion 28 is secured to the forward section of a three-part shaft 29, 85 the sections of which are connected by universal joints 30. Said forward section of the shaft 29 is journaled in the bearing 31 on the clip plate 15 and the rear section thereof is journaled in a bearing 32 on the 90 back of the dash 8. The rear end of the shaft 29 has the same formation as the shaft 18 at 26, to receive and hold the crank 27. As shown, the rear end of the shaft 29 extends into an aperture 33 in the dash 8, and 95 into said aperture, the hub end of the crank 27 may be inserted for connecting the same to the shaft 29.

To hold the crank shaft 10 of the engine against rotation, in a direction to start the 100 engine, when winding the spring, also after said spring is wound, there is formed on the back of the fan pulley 11 a ratchet wheel 34 and co-operating with said ratchet is a gravity held pawl 35. As shown, the pawl 35 is 105 rigidly secured to the forward end of an operating rod 36 and projects radially therefrom. The forward end of the rod 36 is journaled in a bearing 37 secured to the support for the engine 9, and its rear end portion is journaled in a bearing 38 on the 110 under side of the floor 6. At its rear end

the rod 36 is bent laterally to afford a foot crank or arm 39 which projects upwardly through a slot 40 in the floor 6. A suitable guard, not shown, should in actual practice 5 be provided to prevent the arm 39 from being accidentally tripped to throw the pawl 35 into engagement with the ratchet wheel 34.

To move the starter ratchet 13 into interlocking engagement with the starter pin 12 and thereby connect the starter shaft 18 to the crank shaft, there is provided a shipper lever 41 intermediately pivoted to a bearing 42 on the support for the engine 9, and 10 its forked end is connected with the starter shaft 18 by a shipper collar 43. An operating rod 44 is attached to the other end of the shipper lever 41 and extends rearward through a guide sleeve 45 in the dash 8, and 15 is provided with a hand piece 46. Pivoted on the shaft 29 is a spring pressed pawl 47 arranged to engage the teeth of the gear 22 and thereby holds said gear against 20 backward movement under the action of the spring 20. A suitable housing 48 is provided for the improved starter and is secured to the frame 5.

To set the motor 17, the operating rod 44 is first moved endwise, by its hand piece 30 46 toward the dash 8, to swing the shipper lever 41 and thereby impart a rearward endwise movement of the starter shaft 18 against the tension of the spring 14 to interlock 35 the starter ratchet 13 with the starter pin 12. Just before, or just after the operator connects the starter shaft 18 to the crank shaft 10, he operates the arm 39 with 40 the hand piece 46 to move the pawl 35 into engagement with the ratchet wheel 34 and thereby hold 45 said crank shaft against rotation in a direction to start the engine.

With the starter shaft 18 connected to the crank shaft 10, the hand crank 27, when applied to the shaft 29, is turned toward 45 the right to wind the spring 20. When the spring 20 is partly wound, the tension thereof, on the starter shaft 18, which is in a direction to rotate the crank shaft 10 and start the engine, frictionally holds the 50 starter ratchet 13 in engagement with the ratchet 12 and thereby prevents said ratchet 13 from being drawn out of engagement with the starter pin 12 under the action of the spring 14. At this time the crank shaft 55 10 is held against rotation in a direction to start the engine by the pawl 35.

With the starter ratchet 13 frictionally held interlocked with the starter pin 12, the operator may let go of the hand piece 60 46, for the reason that the spring 14 has not sufficient tension to withdraw the starter ratchet 13 out of engagement with the starter pin 12, and continue to operate the hand crank 27 to wind the spring 20. The 65 pawl 47 of course holds the gear 22 against

backward movement under the tension of the spring 20. After the spring 20 has been wound sufficiently tight, the operator may start the engine, at any time, by moving the crank arm 39 with his foot to carry 70 the pawl 35 out of engagement with the ratchet wheel 34 and thereby release the crank shaft 10. With the crank shaft 10 released, the spring 20 becomes active and rotates said crank shaft a sufficient number 75 of times, through the starter shaft 18 and its several connections, to start the engine.

As soon as the engine is started the speed of the crank shaft 10 will, through the starter pin 12, cam the starter ratchet 13 80 out of engagement therewith and return the starter shaft 18 and operating rod 44 to normal positions with the assistance of the spring 14. If desired, the engine may be 85 started by hand in the customary manner by removing the hand crank 27 from the shaft 29 and applying the same to the shaft 18. While the improved starter is shown applied to a Ford automobile, the same may 90 of course be applied to machines of various different makes and designs.

In case the engine back-fires, when cranking the same, the improved starter cannot turn the crank backward, owing to the construction thereof, and possibly injure the 95 operator, as is often the case.

What I claim is:

1. In an internal combustion engine, a starter mechanism comprising a spring motor, means for temporarily connecting said motor to the crank shaft of the engine while winding said motor, and positive means for holding the crank shaft of the engine against the action of said motor in which it operates on said crank shaft to start the engine and for releasing said crank shaft.

2. In an internal combustion engine, a starter mechanism comprising a spring motor, means for temporarily connecting said motor to the crank shaft of the engine while winding said motor, positive means for holding the crank shaft of the engine against the action of said motor in which it operates on said crank shaft to start the engine and for releasing said crank shaft, and connections for winding said motor including means for holding the same against 110 backward movement.

3. In an internal combustion engine, a 120 starter mechanism comprising a shaft, a ratchet for connecting the starter shaft to the crank shaft of the engine, a spring under strain to release the starter shaft from the crank shaft, a spring motor for rotating the starter shaft in a direction to start the engine, means for holding the crank shaft against the action of the motor in which it operates to start the engine and release the 125 same, connections for winding the motor 130

including means for holding the same against backward movement, and connections for moving the starter shaft into a position to connect the ratchet to the crank shaft against the tension of said spring.

4. In an internal combustion engine, a starter mechanism comprising a shaft, a ratchet for connecting the starter shaft to the crank shaft of the engine, a spring under strain to move the starter shaft into a position to release the ratchet from the crank shaft, a gear loosely journaled on the starter shaft, a propelling spring anchored to the starter shaft and to said gear, connections for rotating said gear to wind the propelling spring, a pawl operative on

the gear to prevent backward movement thereof, a pawl and ratchet for holding the crank shaft against the action of the propelling spring in which it operates to start the engine, connections for moving the starter shaft into a position to connect the ratchet to the crank shaft, and connections for releasing said pawl and ratchet to start the motor.

In testimony whereof I affix my signature in presence of two witnesses.

HENRY C. ERBE.
